METHOD OF AND APPARATUS FOR SOFTENING SHOE MATERIALS

Filed Feb. 10, 1923

INVENTOR.

Frederick M. Butler
By his Attorney,
Verna M. Howard

UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

METHOD OF AND APPARATUS FOR SOFTENING SHOE MATERIALS.

Application filed February 10, 1923. Serial No. 618,374.

This invention relates to the treatment of materials in process of manufacture for the purpose of softening them, and especially to the treatment of shoe materials. The present application is filed as a continuation in part of my copending application Serial No. 342,883, filed December 6, 1919, and includes not only the subject-matter of the former said application but subject-matter 10 not therein disclosed.

For the purpose of illustrating a preferred form of apparatus embodying the invention the accompanying drawings show an apparatus designed to soften the vamps and toe 15 stiffeners of assembled shoes preparatory to the usual pulling-over operation. The construction of this apparatus is such that the materials to be treated may conveniently be in a substantially flat condition and be separated from the forepart of the last while the rear portion of the upper is attached to the last, but in some respects the invention is capable of being embodied in other forms and is adapted to be used at other stages in 20 the manufacture of shoes. For example, certain features of the invention are well adapted to be used in an apparatus designed more particularly to soften pulled-over toes preparatory to lasting.

An object of the invention is to provide 30 improved methods of supplying moisture to the materials that require softening and to provide improved apparatus adapted to administer treatment according to said methods. The invention provides for all the desirable regulations of moisture and heat to 35 suit the various requirements of different kinds of leather and stiffening materials and to suit also the preferences of the user, with a view to making the apparatus and the treatment to be practised therewith as nearly 40 universal as possible and to safeguard the materials against being burned or otherwise injured.

More specifically, an object of the invention 45 is to provide an apparatus and a method of operation that will minimize the moistening of the atmosphere in the work-room. In this respect the invention provides for generating enough, but not necessarily more 50 than enough, moist vapor to accomplish the

desired softening treatment, and provides for supplying the vapor in such a way that it may be nearly if not wholly absorbed by the work.

A feature of the invention consists in a heat-radiating element arranged adjacent to a work-station, and means arranged to supply liquid such as water to that surface of the heat-radiating element that confronts the work, from a source of supply at a lower level, by the motive force of the medium that heats said element. The heat-radiating element is preferably located so close to the work that the vapor generated thereby will have no appreciable distance to travel to reach the work, excepting as it may spread laterally in the space between the heat-radiating element and the work. An advantage of supplying hot moist vapor in this way is that the quantity may be regulated with the utmost accuracy by regulating the quantity of water supplied to the heat-radiating element, while the temperature of the vapor may be regulated by regulating the heating medium.

For softening vamps and toe-stiffeners preparatory to pulling-over, the invention preferably comprises a heat-radiating element formed to enter between the upper and last of an assembled shoe, in which case the invention consists further in supplying the water between the upper and the last with which it is assembled. I consider myself the first to provide softening treatment for an assembled shoe by supplying water between the upper and the last and there converting the water into hot moist vapor, and I therefore desire protection of correspondingly broad scope.

The illustrated apparatus is designed to use steam as the heating medium and comprises a steam-chest for radiating heat to the work and for vaporizing the water that is used to moisten the work. In this connection a feature of the invention consists in utilizing water of condensation that accumulates in the steam-chest to supply the moisture that is used to treat the work, and consists further in utilizing steam-chest pressure to transfer the water to the external surface of the chest that confronts the work.

to be treated. In this respect the apparatus and its operation are comparable to those of the well-known siphon-bottle.

Another object of the invention is to 5 spread the vapor laterally and to distribute it evenly throughout a relatively great area so that a plurality of articles of work or a single article of great lateral dimensions may be moistened uniformly at all points. 10 This is accomplished, according to the illustrated construction, by providing a foraminous plate between the work and the vaporizing surface and by restricting the openings in said plate to an extent that compels the 15 vapor to spread laterally from the point of vaporization to all points of the plate to find the necessary aggregate means of escape. Although the holes in the plate are relatively close to each other they are so small that 20 their aggregate area is not sufficient to release all the vapor. Furthermore, the foraminous plate serves to safeguard the work against being burned and against being moistened too rapidly. Any surplus of vapor 25 will escape beyond the area of the plate as, for example, through the port which receives the water to be vaporized and through crevices between the plate and its supporting structure. Atmospheric pressure is 30 therefore maintained at all times under the plate.

Another feature of the invention consists in providing for two alternative modes of operating the apparatus, by one of which the 35 treating vapor may be restricted with respect to quantity by restricting its temperature to a point below the boiling temperature, and by the other of which a more copious supply may be administered to the 40 work by increasing its temperature to a point above the boiling temperature. The control as to these two modes of operation is subject to the will of the user, and the change from one to the other and vice versa 45 is obtainable by regulating the temperature of the foraminous plate. For example, the temperature of this plate is never as high as that of the heating element, and the difference, while not necessarily constant, may 50 be such as to enable the plate to condense the vapor that is generated by the heating element. Now, therefore, if the temperature of the plate were say 200 degrees F. while that of the heat-radiating element is 55 220 degrees, the plate would condense the vapor generated by the heating element. The holes in the plate are so small that when filled with water the water will be supported in them by surface tension. Conse- 60 quently, in practice, as the vapor becomes condensed by the plate under the thermal conditions above defined, the holes in the plate become sealed with plugs of water. Still, the temperature of the plate, while not 65 sufficient to boil the water, is nevertheless

sufficient to cause enough evaporation of the sealing plugs to moisten the shoe upper in the space of time it would ordinarily have to remain in position for treatment. The temperature of this moisture rising from the 70 plate would of course be considerably less than that of the vapor under the plate and would safeguard even the most delicate leathers against scorching, regardless of how long the work might remain in position for 75 treatment. Furthermore, the quantity of moisture rising from the plate would be determined by the temperature of the plate rather than by the quantity of vapor generated under the plate. 80

On the other hand, to apply the hotter vapor directly to the work the user would have merely to regulate the heating means to maintain the foraminous plate at a temperature above 212 degrees. Under the latter condition, the vapor under the plate would rise as such through the holes in the plate and act on the work without being condensed by the plate, and the volume of moisture received by the work would be greater 90 than under the aforesaid lower thermal conditions.

For efficiency of operation the steam-chest is preferably cylindric, that shape affording the greatest heating capacity in proportion 95 to the size and weight of the chest. The increased heating efficiency makes it feasible to make the radiating fin solid and relatively thin instead of hollow and relatively thick as in my former said construction. The latter construction is therefore less costly and better adapted to conform to the requirements of the work, especially in treating small sizes.

The steam-chest is preferably made of three major elements, viz, two confronting headers and a tubular body member arranged between them. This construction enables the headers to remain permanently joined to a supply pipe and an exhaust pipe respectively and at the same time provides for removing the body portion, as for cleaning or repairs, without disturbing the piping connections. It also provides for an inexpensive three-point bearing or stand, since 100 each of said major elements may be provided with a foot portion to rest on a bench or other supporting surface.

Other objects and novel features are hereinafter described and claimed and, so far as the apparatus is concerned, are illustrated by the accompanying drawings.

Referring to the drawings,

Fig. 1 is an end elevation partly in section of an apparatus constructed in accordance with this invention, the figure including a last and an upper as assembled preparatory to the pulling-over operation, the rear part of the upper being fastened to the heel end of the last as by a tack, while the vamp is sep- 115 120 125 130

arated from the last and is arranged in position for treatment;

Fig. 2 is a vertical section through the apparatus as indicated by broken line 2-2 of Fig. 1, portions of the apparatus being broken out merely to save space on the drawing;

Fig. 3 is a plan view of a portion of the foraminous plate that forms the upper wall of the vaporizing chamber; and

Fig. 4 is a vertical section of a portion of the structure intersected by broken line 4-4 of Fig. 1, to show how the ends of the vaporizing chamber are formed.

A hollow metallic structure providing a steam-chest is formed in part by a tubular body portion 10 and in part by detachable end pieces or headers 11 and 12. These headers are fastened to the ends of the body portion by bolts 13, and the joints are made steam-tight by suitable gaskets 14. When the apparatus is designed to be installed on a bench it is preferably provided with three bearing points so that it will not require truing to avoid wobbling. Accordingly, as shown, the body portion 10 is provided, midway of its ends, with a bearing piece 15, and each of the headers is formed with a bracket portion 16 having a boss or bearing portion 17. The brackets 16 also afford convenient means for holding a shelf 18 for supporting one or more lasts 42 as shown by Fig. 1. The shelf 18 may be a board long enough to reach from one bracket 16 to the other and may be fastened to the brackets by screws 19. A substantially upright board 20 may be attached to the upper surface of the shelf 18 to serve as a stop to prevent inserting the lasts too far. The member 20 is bored to receive two bolts one of which is indicated at 21 and both of which extend through the shelf 18 and carry wing nuts 22 by which to clamp the member 20. The shelf 18 is preferably provided with slots 23 to receive the clamping bolts and to afford a range of adjustment of the member 20 relatively to the shelf.

A pipe 24 for supplying steam is coupled to the header 11, and a return or exhaust pipe 25 is coupled to the header 12. These pipes are provided respectively with a supply valve 26 and an exhaust valve 27 by which the volume and pressure of steam in the chest may be regulated. The water of condensation indicated at 28 may accumulate in the steam-chest up to the level of the outlet pipe 25 to provide moisture for the work as hereinafter explained. The hollow body member 10 of the steam-chest has a substantially horizontally projecting portion 29 arranged to overhang the fore-parts of the lasts placed on the shelf 18, to conduct the heat from the steam and to radiate such heat between the lasts and the vamps. This heat-radiating portion 29 has relatively great lateral dimensions to under-

lie from four to six vamps at once. Furthermore, the portion 29 is pan-shaped or dished to provide a relatively shallow chamber 30 in which water may be vaporized between the lasts and the vamps 31.

The water of condensation that accumulates in the steam-chest may be caused to flow to the chamber 30 by the pressure of the steam in the chest, in which respect the action is comparable to the siphonic action of a siphon-bottle. For this purpose a pipe 32 is arranged to extend through one wall of the steam-chest so that its receiving end will be immersed in the water of condensation. This pipe, including the necessary fittings, conducts the water under pressure to a discharge nozzle 33 above the steam-chest. The body of the steam-chest is formed with a funnel-shaped boss 34 to receive the water so discharged, said boss having a hole through which the water drops so that it may flow on the pan-shaped portion 29 to be vaporized.

That part of the chamber 30 over which the vamps are arranged for treatment is provided with a detachable cover consisting of a thin foraminous plate 35 hereinbefore mentioned, the edges of said plate being arranged to rest on the upright walls of the chamber and being held preferably by some means that will permit it to be detached quickly. This plate is provided with a large number of closely spaced holes 36 preferably no larger than, if as large as, the shank of a common pin. It has been found in practice that holes this size will hold water by surface tension and that they become sealed with water of condensation when the temperature of the plate is below the boiling temperature. A grid, consisting of a sheet of wire fabric 37, is placed on the plate 35 to support the vamps out of contact with the plate. This grid enables the vapor to spread laterally between the plate and the work and to become distributed evenly to all portions of the work. A grooved bar 38 is attached to the heat-radiating portion 29 to clamp both the wire grid 37 and the plate 35 to the portion 29. This clamping device 38 is preferably made of some material that will not conduct heat readily and may be made most economically of wood such as maple. It is preferably coextensive with the portion 29 and plate 35, and is bored at suitable intervals for the reception of screws 39 which extend into tapped holes formed in the portion 29. The clamping device has a hook-shaped portion 40 that extends around the front edges of the plate and grid and bears on the top of the grid with sufficient pressure, when the screws 39 are tightened, to hold the plate and grid against slipping. This clamping device occupies a position where it is adapted to be engaged by the instep portions of the lasts,

110
115
120
125
130

provided the toe board 20 is not set out far enough to prevent such engagement. In this respect the clamping device constitutes an additional guard to prevent the lasts from 5 being indented or chipped by striking the cast iron of which the heat-radiating element is made, and also prevents the uppers from being burned by engagement with the heat-radiating element.

10 When the apparatus is installed for use the pipe 24 will be connected to any convenient source of steam, the pressure of which may be high or low. The pressure and temperature of the chest will depend 15 upon how much or how little the valves 26 and 27 are opened. In a comparatively short space of time water of condensation will accumulate in the bottom of the chest and thereafter it will be maintained at a constant level determined by the outlet through 20 which the exhaust is conducted. The steam pressure in the chest will force the water of condensation through the pipe 32 which is provided with a valve 41 by which the quantity 25 of water discharged from the nozzle 33 may be regulated or even cut off entirely if desired. Assuming that an article of work is arranged as shown by Fig. 1, the last will not be appreciably affected by the heat or 30 moisture supplied by the apparatus, but the vamps 31 will receive treatment according to regulation of the valves 26 and 27 and 41. If the valve 41 is closed tightly while the valves 26 and 27 are open the vamps 35 will be heated without receiving any moisture, since the heat is supplied exclusively by radiation. Although the portion 29 would ordinarily be maintained at a temperature sufficient to boil water the heat 40 radiated therefrom will not injure the work because the plate 35 remains at a much lower temperature and acts as a baffle or screen, and because the work is spaced from the plate by the wire grid 37. The efficiency 45 of the apparatus is increased by providing the vaporizing chamber with upstanding ribs 50 integral with the portion 29, to radiate heat and to brace the plate 35. Since the vamps do not engage anything 50 but the non-conducting clamping member 38 and the wire mesh 37 they are safeguarded against being burned.

In most cases it is desirable to administer some moisture with the heat, the necessary 55 quantity of moisture being small in all cases but being more for some kinds of leather than for others. For example, certain colored leathers would be discolored by a quantity of moisture that would expedite 60 the softening of certain other leathers without harming them. Whatever the requirements may be, they may be satisfied by adjusting the three valves. Assuming that the steam-chest has been heated to the desired 65 temperature, and that the work to be treat-

ed requires moisture, any desired quantity of vapor may be generated in the chamber 30 by opening the valve 41 to the desired extent. As the water drops from the nozzle 33 it flows into the chamber 30 and spreads laterally to form a thin film and is converted into vapor almost instantaneously. In no case would the requisite amount of moisture be so great as to call for a quantity of water that would spread over the entire surface of the bottom of the chamber 30 before it would be converted into vapor.

The apparatus therefore operates as a flash boiler, and the slight pressure in the chamber 30 due to expansion causes the vapor to spread laterally from the center of vaporization to all parts of the plate 35 seeking to escape through the holes 36, since the aggregate area of all the holes is not quite enough to relieve the pressure. The pressure is, of course, almost negligible because the relatively remote hole for the water supply is always open.

In practice the valve 41 would be the most convenient means for regulating the rate of flow of water to the chamber 30, but whether there would or would not be a flow of water would depend primarily upon the valves that regulate the heating medium. For example, assuming that the valve 41 is in the most desirable position of regulation, and that it is desired to keep it there, it is possible to stop the flow of water by manipulating the valves 26 and 27. At the end of a working period the valve 26 would be closed to turn off the heat, and this would also turn off the flow of water because there would be no pressure in the steam-chest to discharge the water. On resuming the operation of the apparatus after an interval of non-use it would only be necessary to open the valve 26 to supply heat and also to supply the motive force for discharging water from the nozzle 33, and if it were desired to leave the valve 41 open at some predetermined position of regulation, but to postpone the discharge of water until the apparatus is hot enough to vaporize it, it would only be necessary to adjust the valve 27 to relieve the pressure in the steam-chest, thus providing rapid circulation of steam through the chest without developing pressure therein. Having permitted the steam to heat the chest to the desired working temperature, the discharge of water would be brought about by regulating the valve 27 to restrict the exhaust to a point that would develop a slight pressure in the chest. From the foregoing it may be seen that the apparatus is also capable of heating the work without moistening it, and that when water has been used it will not in any case continue to flow after the heating medium has been turned off.

The described apparatus is such that by regulating the steam valves 26 and 27 the

plate 35 may be heated to a temperature above 212 degrees F. or its temperature may be maintained considerably below that point while the temperature of the heating element 29 is maintained considerably above that point. If the regulation is such that the temperatures of the plate and heating element are maintained respectively below and above 212 degrees the plate will condense the vapor seeking to pass through its holes, and the latter will therefore be sealed with plugs of water which will be supported by surface tension and will undergo continuous evaporation above and continuous replenishment from below by more vapor and condensation thereof.

In many cases the last-described mode of operation will supply sufficient moisture to the work, since the evaporation of the many small segregated bodies of water in the holes of the plate will be moderately rapid because of their nearness to the boiling temperature. Still, if a greater volume of moisture is desired, it may be readily supplied by regulating the heating means to maintain the temperature of the plate 35 above 212 degrees. Then the vapor rising from the heating element 29 will not be condensed by the plate but will pass through the holes as vapor and reach the work without going through an intermediate stage of condensation. Furthermore, its temperature will be higher than that of the vapor given off by the plugs or seals of water in the holes of the plate.

The apparatus illustrated herewith is more efficient and less costly than that disclosed in my former said application. The cylindric shape of the body of the steam-chest conserves the heat and maintains the vaporizing portion 29 at an effective temperature with comparatively small consumption of steam. When it is necessary to clean the steam-chest or to remove it for any other purpose it is not necessary to disturb the steam-piping or disconnect it from the headers 11 and 12, since the body of the steam-chest may be lifted from between the headers after removing the bolts 13.

Having thus described my invention, what I claim as new and desire to secure by Letters Patent of the United States is:

1. A softening apparatus comprising a heat-radiating element formed to enter between the last and upper of an assembled shoe, and means for supplying a liquid to said element.

2. A softening apparatus comprising a dry heat-radiating element and work-engaging means spaced from and fastened to each other, both being formed to intervene between a last and a portion of a shoe-upper assembled therewith.

3. A softening apparatus comprising a dry heat-radiating element and work-engaging means spaced from and fastened to each

other, both being formed to intervene between a last and a portion of a shoe-upper assembled therewith, and means arranged to supply a treating agent between said element and the work-engaging means. 70

4. A softening apparatus comprising regulatable heating means and vamp-supporting means spaced from and fastened to each other, both being formed to intervene between a last and the vamp of a shoe-upper assembled therewith, and means regulatable independently of said heating means to supply a fluid treating agent between the heating means and the vamp-supporting means. 75

5. A softening apparatus comprising work-engaging means formed to maintain a portion of a shoe-upper apart from a last with which the upper is assembled, means constructed and arranged to radiate dry heat between the last and said work-engaging means, and means for supplying a fluid treating agent between the two aforesaid means. 80

6. A softening apparatus comprising means constructed and arranged to radiate dry heat and formed to intervene between a last and a portion of a shoe-upper assembled therewith, means arranged to maintain said portion of the upper out of contact with said heat-radiating means, and means arranged to supply a fluid treating agent between the two aforesaid means. 85

7. A softening apparatus comprising a dry-heat radiator and a grid fastened to but spaced from each other and formed to intervene between a last and a portion of a shoe-upper assembled therewith, and means arranged to supply a vaporizable fluid between the radiator and the grid. 100

8. A softening apparatus comprising a steam-chest having an imperforate portion formed to intervene between a last and a portion of a shoe-upper assembled therewith, and means arranged to supply a fluid treating agent to an external surface of said imperforate portion. 105

9. A softening apparatus comprising a heat-radiating element having an imperforate portion formed to intervene between a last and a portion of an upper assembled therewith, and means for supplying a vaporizable liquid to a surface of said imperforate portion. 115

10. A softening apparatus comprising a steam-chest having a space arranged to contain water, and a conduit connected to the water-space of said chest and arranged to supply water to an external surface of said chest from the products of condensation of the steam used to heat the chest. 120

11. A softening apparatus comprising a steam-chest, and a conduit arranged to convey the products of condensation from the interior of said chest to a point of discharge over the chest so that the products dis- 125

65 130

charged at said point will flow on an external surface of the chest.

12. A softening apparatus comprising a steam-chest, a conduit arranged to conduct the products of condensation from the interior of the chest to a point of discharge adjacent to an external surface of the chest so that the products discharged at said point will flow on said surface, and a conduit leading out of said chest above the level of the receiving end of the first said conduit to conduct away the used steam separately from the products of condensation.

13. A softening apparatus comprising heating means, means for regulating the temperature thereof, and means arranged to supply a liquid treating agent under control of said regulating means to an external surface of said heating means.

20 14. A softening apparatus comprising a steam-chest for radiating heat to an article of work, and means arranged to supply water from the interior of said steam-chest to an external surface thereof adjacent to the work-station by the fluid pressure in the chest.

25 15. A softening apparatus comprising work-supporting means, and means including a pressure-sustaining steam-chest constructed and arranged to treat the work on said supporting means with hot moist vapor derived from water of condensation in said steam-chest.

30 16. A softening apparatus comprising steam-heated means for radiating heat to the work, said means having an inlet valve and an outlet valve to control the effective pressure of steam therein, and means arranged to supply water, under said pressure, from the lower part of said steam heated means to the external surface that confronts the work.

35 17. A softening apparatus comprising chamber-forming means, means for conducting a heated fluid under pressure to the chamber in said means, and a conduit arranged to conduct a fluid treating agent from said chamber by the pressure in the chamber, said conduit being arranged to discharge said treating agent upon a heated external surface of said chamber-forming means.

40 18. A softening apparatus comprising a hollow heat-radiating element a portion of which is formed to intervene between a last and the vamp of a shoe-upper assembled therewith, means for supplying steam under pressure to the chamber in said element, and means constructed and arranged to conduct the products of condensation from said chamber and to discharge them on the surface of said intervening portion.

45 19. A softening apparatus comprising a steam-chest having a portion formed to intervene between a last and the vamp of a shoe-upper assembled therewith, vamp sup-

porting means arranged to maintain a space between the vamp and said intervening portion, and means arranged to conduct the products of condensation of the steam used to heat said chest to said space and to discharge said products into the air so as to flow on an upper surface of said intervening portion.

20 20. A softening apparatus comprising elongated heating means formed to intervene between a series of lasts and the vamps of shoe-uppers assembled with the lasts, means arranged to support the vamps so as to provide a space between the vamps and an upper surface of said heating means, and means arranged to discharge a liquid treating agent so that it will flow in said space and on said surface to be vaporized by the heat of the latter.

25 21. A softening apparatus comprising means constructed and arranged to intervene between a last and a portion of a shoe-upper assembled therewith to maintain a space, and means constructed and arranged to conduct a liquid treating agent into said space and to vaporize the liquid in said space.

30 22. A softening apparatus comprising a steam-chest, means arranged to maintain an article of work adjacent to but out of contact with an external surface of the steam-chest, means arranged to circulate steam through said chest, and means arranged to conduct to said surface, to be vaporized thereby, the products of condensation of the steam used to heat the chest, the latter said means being regulatable independently of the steam supplied to the chest.

35 23. A softening apparatus comprising a heating element having heat-radiating fins projecting upwardly from an upper surface, a work-supporting grid fastened to said element and arranged to lie on said fins, and means arranged to discharge a liquid treating agent on said element so that it will flow on said surface between said fins.

40 24. A softening apparatus comprising a heating element and means for regulating the temperature thereof, vamp-supporting means fastened to said element and arranged to overlie the latter, confronting portions of said element and the vamp-supporting means being spaced apart and formed to intervene between a last and the vamp of a shoe-upper assembled therewith, means for discharging a liquid treating agent on said element so that it will flow thereon into the space between said confronting portions, and means for controlling the volume of liquid so discharged.

45 25. A softening apparatus comprising means for radiating dry heat from a moist and heated treating fluid, means for supporting an article of work in position to be

heated thereby, and means constructed and arranged to siphon the liquid constituents of the fluid that has been used to heat the first said means to the field of radiation of the first said means so that the radiant heat will convert said liquid into moist vapor and supply said vapor to the work to moisten the latter.

26. A softening apparatus comprising a work-support, a steam-conduit connected to a source of steam under pressure and arranged to radiate dry heat to an article of work sustained by said work-support, and a conduit arranged to conduct to the field of radiant heat the condensed constituents of the steam that has given up its heat to the work.

27. A softening apparatus comprising regulatable dry heating means formed to enter between the last and upper of an assembled shoe, and means arranged to supply a liquid between said heating means and the upper to be vaporized by the heat, said two means being so related that the supply of liquid is dependent upon the application of heat to said heating means.

28. That method of treating shoe materials which consists in heating the work by causing steam to heat a radiator adjacent to the work, and simultaneously moistening the work by causing water of condensation from the steam so used to flow on that surface of the radiator that confronts the work.

29. That method of treating shoe-materials which consists in supplying a liquid treating agent between a shoe-element and a last assembled therewith, and vaporizing said treating agent by radiating heat between the shoe-element and the last.

30. That method of treating shoe-materials which consists in supplying a liquid treating agent between a shoe-element and a last assembled therewith, maintaining the shoe-element out of contact with the liquid, and vaporizing the latter by radiating heat between said element and the last.

31. That method of treating shoe-materials which consists in maintaining a shoe-element out of contact with a last with which it is assembled, to provide a space between said element and the last, causing a vaporizable liquid to flow into said space without touching the shoe-element, and vaporizing the liquid in said space by radiating heat therein.

32. That method of producing hot moist vapor to treat shoe materials which consists in supplying water to a level adjacent to the work from a lower level by the motive force of a heating medium, and vaporizing said water adjacent to the work by said heating medium.

33. That method of producing hot moist vapor to treat shoe-materials which consists in spreading water under one or more

work-stations to form a thin sheet or film, causing a heating medium to vaporize said sheet or film of water, and replenishing said water with water supplied from a lower level by the motive force of said heating medium.

34. That step in methods of generating hot vapor to treat shoe-materials which consists in supplying water to a heat-radiating element from a source of supply at a lower level by the action of the heating medium that heats said element.

35. That method of generating vapor to treat shoe-materials which consists in vaporizing a body of water under the work by radiating heat into said water, and maintaining a substantially constant quantity of water in the vaporizing locality by replenishing said body under control of the heating medium.

36. A softening apparatus comprising a work-support, means for radiating dry heat to the work on said support from a locality under the work, and means arranged to supply water to the field of radiant heat under the work there to be vaporized by the radiant heat, said water-supplying means being controllably related to said heat-radiating means so that the former can function only when the latter functions.

37. That method of treating shoes which consists in separating a portion of the upper from the last of an assembled shoe, and converting a liquid into hot moist vapor between the last and said portion of the upper.

38. A softening apparatus comprising a steam-chest for radiating heat to the work, said chest having a steam-inlet and a steam-outlet for circulating steam therethrough and having a water-space below said outlet, and means arranged to supply water from said space to flow on the external surface confronting the work.

39. A softening apparatus comprising a steam-chest for radiating heat to the work, and siphonic means arranged to supply water from the interior of said chest to flow on the external surface that confronts the work.

40. A softening apparatus comprising a steam-chest for radiating heat to the work, said chest having an interior space for water of condensation, and a conduit arranged to conduct said water of condensation to an external surface of the chest at a higher level than said water, the receiving end of said conduit being arranged to be immersed in said water to enable the steam-chest pressure to force the water of condensation to the higher level.

41. A softening apparatus comprising a heat-radiating element adjacent to a work-station, and means arranged to supply a liquid to that surface of the heat-radiating

element that confronts the work, from a source of supply at a lower level, by the motive force of the heating medium that heats said element.

42. A softening apparatus comprising a tubular body member and two headers fastened to the ends thereof to form a closed steam chamber, a shelf connecting and supported by said headers to support one or more lasts, said body member having a laterally projecting pan-shaped portion formed and arranged to overhang the foreparts of lasts arranged on said shelf, means for supplying water to said pan-shaped portion to be converted into hot moist vapor by radiant heat, and a grid arranged over said pan-shaped portion to support the vamps of uppers attached to the heel-parts of the lasts so that the vamps will be heated and moistened.

43. A softening apparatus comprising a steam-chest having a laterally projecting pan-shaped heat-radiating portion, and means for supplying water to said portion.

44. A softening apparatus comprising a steam-chest having a pan-shaped heat-radiating portion, a foraminous plate arranged to cover said portion, upstanding projections formed on said pan-shaped portion to brace said plate and to radiate heat, and means for supplying water to said pan-shaped portion.

45. A softening apparatus comprising two confronting headers each having a bracket portion, a work-supporting shelf connecting said bracket portions and fastened to each, a tubular member arranged between and detachably fastened to said headers to form, conjointly with the latter, a pressure-sustaining steam-chest, said tubular member having a projecting portion for radiating heat to work arranged on said shelf.

46. A softening apparatus comprising a steam-chest consisting of three major elements, viz, two headers and a tubular member arranged between them, said headers having flat confronting surfaces seated against the ends of said tubular member and having provisions for coupling to a supply pipe and an exhaust pipe respectively, and means for fastening said headers to said tubular member, each of said major elements having a foot to provide the assemblage with a three-point bearing or stand.

47. A softening apparatus comprising an element for radiating heat to the work, means for supplying water between said element and the work to be vaporized by the heat, and a foraminous baffle member arranged between said element and the workstation to spread the vapor by restricting its flow to the work.

48. A softening apparatus comprising an element for radiating heat to the work, means for supplying water between said ele-

ment and the work to be vaporized by the heat, and a foraminous metallic member arranged between said element and the workstation to control the flow of vapor to the work, the aggregate area of the holes in said member being less than enough to release all of the vapor at atmospheric pressure.

49. A moistening apparatus comprising means for supplying hot moist vapor at substantially atmospheric pressure, said means including a metallic heat-radiating element having emission holes so small that water of condensation will automatically form seals therein by reason of surface tension.

50. A moistening apparatus comprising a thin metallic plate, and means for supplying hot moist vapor at substantially atmospheric pressure to one side of said plate, the latter having emission holes so small that water of condensation will automatically form seals therein by reason of surface tension.

51. A moistening apparatus comprising a thin plate arranged to underlie the work, means for supplying hot moist vapor at atmospheric pressure to the under side of said plate, the latter having emission holes so small that water of condensation supported therein by surface tension will fill them, and means to heat said plate.

52. A moistening apparatus comprising means forming a vaporizing chamber and including a top plate of thin sheet metal and a heater for converting water in the chamber into hot moist vapor at atmospheric pressure, said top plate having emission holes so small that if the vapor condenses in them the water of condensation will fill them and form complete closures by reason of surface tension.

53. A moistening apparatus comprising a heat-radiating element the upper surface of which is dished to form a pan, means arranged to supply water to said pan to be converted into hot moist vapor by the heat of the pan, and a thin sheet metal plate arranged to cover said pan and having emission holes so small that if the vapor condenses in them the water of condensation will fill them, said heat-radiating element having ribs extending upwardly from the bottom of the pan and touching said plate to support the latter and to transmit heat thereto.

54. A moistening apparatus comprising means for supporting an article of work, means formed and arranged to support by surface tension a plurality of small separate bodies of water under and adjacent to the work, and means for heating said bodies of water to convert them into hot moist vapor.

55. A moistening apparatus comprising means for supporting an article of work, means formed and arranged to support by

surface tension a plurality of small separate bodies of water under and adjacent to the work, and means for supplying hot moist vapor at atmospheric pressure to the under side of said water-supporting means to supply and replenish the small bodies of water by condensation.

56. A moistening apparatus comprising a foraminous plate the holes in which are so small as to hold enough water by surface tension to keep them sealed, means arranged to heat said plate to convert the water in said holes into hot moist vapor, and means arranged to supply water to said heating means so that it will be converted into hot moist vapor and flow under said plate to fill said holes with water of condensation and thereafter replenish them as the water therein is re-vaporized.

20 57. A moistening apparatus comprising a
steam-chest having an external dished portion
arranged to hold water, a vapor-dispensing plate arranged over said dished portion
to form a cover therefor, said plate having
25 holes so small that water held in them by
surface tension will seal them, and means ar-
ranged to conduct water of condensation
from the interior of said steam-chest to said
dished portion by the pressure in the steam-
30 chest so that it will be converted into hot
moist vapor by the dished portion and rise
as vapor to fill and replenish said holes with
water of condensation.

58. A moistening apparatus comprising
35 means forming a vaporizing chamber and
having a vent to maintain atmospheric pressure
therein, means for supplying water to
said chamber, and means for heating the bot-
tom of the first said means to convert the
40 water into hot moist vapor, the cover of said
chamber having emission holes so small that
the quantity of water that will be supported
in them by surface tension will seal them.

45 59. A moistening apparatus comprising a foraminous plate arranged to underlie a work station, the holes in said plate being so small that water enough to fill them will be supported in them by surface tension, means to supply hot moist vapor at atmospheric pressure under said plate, and means to regulate the temperature of said plate to maintain it above or below the boiling temperature, as desired.

60. A moistening apparatus comprising
means to supply hot moist vapor at atmos-
pheric pressure between the last and vamp
of an assembled shoe, and means to reduce
the temperature of said vapor before it
reaches the vamp.

60 61. A moistening apparatus comprising
means to generate hot moist vapor at atmos-
pheric pressure between the last and vamp
of an assembled shoe, and means to reduce
the temperature of said vapor before it
reaches the vamp.

62. A moistening apparatus comprising means to supply hot moist vapor at atmospheric pressure under and adjacent to a work station, and thermally regulatable means arranged to condense said vapor and re-evaporate it at a lower temperature before it reaches the work. 70

63. That method of heating and moistening an article of work which consists in supporting by surface tension a plurality of small segregated bodies of water under and adjacent to the work, and converting such water into hot moist vapor. 75

64. That method of supplying hot moist vapor to treat an article of work which consists in supporting a plurality of small segregated bodies of water under and adjacent to the work, converting such water into hot moist vapor, and replenishing said bodies of water individually as they become converted into vapor as aforesaid. 80 85

65. That method of supplying hot moist vapor to treat an article of work which consists in supporting a plurality of small segregated bodies of water at predetermined points under and adjacent to the work, and simultaneously converting said bodies of water into hot moist vapor and replenishing them individually with more water. 90

66. That method of supplying hot moist vapor to treat an article of work which consists in supporting a plurality of small segregated bodies of water of predetermined volume under and adjacent to the work, and simultaneously converting said bodies of water into vapor and replenishing them individually with more water to maintain a substantially constant volume in each of them. 95 100

67. That method of supplying hot moist vapor to treat an article of work which consists in supporting a plurality of small segregated bodies of water under and adjacent to the work, converting said bodies of water into hot moist vapor, and supplying hot moist vapor to said bodies of water to replenish them with products of condensation. 105 110

68. That method of supplying hot moist vapor to treat an article of work which consists in supporting a plurality of small segregated bodies of water under and adjacent to the work, converting said bodies of water into hot moist vapor, and supplying hot moist vapor to the under sides of said bodies of water to replenish them with water of condensation. 115 120

69. That method of supplying hot moist vapor to treat an article of work which consists in converting water into hot moist vapor, spreading said vapor laterally to effect substantially uniform distribution thereof within a predetermined area, maintaining said vapor out of contact with the work, condensing said vapor under the work, supporting by surface tension a plurality of 125 130

small segregated bodies of water so condensed, and converting said small bodies of water into hot moist vapor within treating range of the work.

- 5 70. That method of producing hot moist vapor to treat an article of work which consists in supplying hot moist vapor at atmospheric pressure under the work station, baffling said vapor to distribute it laterally and 10 keep it below the work station, condensing said baffled vapor while so distributed, supporting the water of condensation by surface tension under and relatively close to the work station, and re-converting said water 15 of condensation into moderately hot moist vapor within treating range of the work station.
71. An apparatus for treating shoe materials comprising a pressure-sustaining steam-chest, means to drain water of condensation from the bottom of said chest and deliver it to an upper surface thereof to be converted into vapor, and means to support an article of work in the field of such vapor.
- 25 72. An apparatus for treating shoe ma-

terials comprising work-supporting means providing a series of work-stations, a steam-heated structure having a pressure-sustaining steam-chest and a heat-radiating portion arranged to extend under and adjacent to each of said work-stations, and means to drain water of condensation from the bottom of said steam-chest and deliver it to the upper surface of said heat-radiating portion to be converted thereby into vapor to treat the work at said stations.

73. A treating apparatus comprising means to support one or more shoes on lasts in position for treatment, heat-radiating means formed and arranged to overhang the toes of the lasts and underlie the vamps of the shoes, and a bar of heat-insulating material arranged in front of the forward edge of said heat-radiating means to arrest the lasts by engagement with the instep portions thereof.

In testimony whereof I have signed my name to this specification.

FREDERICK M. FURBER.
